Primary Examiner—B. J. Bullock(74) *Attorney, Agent, or Firm*—Dickstein, Shapiro, Morin & Oshinsky, LLP(57) **CLAIM**

The ornamental design for a wall plate, as shown and described.

DESCRIPTION

FIG. 1 is a perspective view of a first embodiment of the design, showing a wall plate having a built-in modem.

FIG. 2 is a front view of the wall plate shown in FIG. 1, showing surge protection and ground indicator lights disposed on the top portion above the outlet openings.

FIG. 3 is a side view of the wall plate shown in FIG. 1.

FIG. 4 is a bottom view of the wall plate shown in FIG. 1. FIG. 5 is a top view of the wall plate shown in FIG. 1, showing two modem ports, one for input and one for output.

FIG. 6 is a perspective view of a variant of the second embodiment of the design, showing a wall plate for a light switch in addition to electrical outlets, and having built-in cable or network connection capabilities.

FIG. 7 is a front view of the wall plate shown in FIG. 6, showing surge protection and ground indicator lights disposed on the top portion above the outlet openings, and two coaxial cable connection ports extending from the top portion on the left side of the figure.

FIG. 8 is a side view of the wall plate shown in FIG. 6. FIG. 9 is a bottom view of the wall plate shown in FIG. 6; and,

FIG. 10 is a top view of the wall plate shown in FIG. 6, showing the two coaxial cable connection ports, one for input and one for output, provided on the left side of this surface, and the two coaxial connections ports, one for input and one for output, provided on the right side of this surface.
